UNITED STATES PATENT OFFICE.

OTTO C. HAMEL, OF WYOMISSING, PENNSYLVANIA, ASSIGNOR TO MEINIG HOSIERY CO., OF READING, PENNSYLVANIA, A CORPORATION OF PENNSYLVANIA.

DESIGN FOR A STOCKING.

Application filed March 16, 1929. Serial No. 30,500. Term of patent 14 years.

To all whom it may concern:

Be it known that I, OTTO C. HAMEL, a citizen of the United States, residing at Wyomissing, in the county of Berks and State of Pennsylvania, have invented a new, original, and ornamental Design for Stockings, of which the following is a specification; reference being had to the accompanying drawing, forming part thereof.

The figure is a rear view of a stocking, showing my new design.

I claim:

The ornamental design for a stocking, as shown.

In testimony whereof I affix my signature.

OTTO C. HAMEL.
